UNITED STATES PATENT OFFICE.

ROBERT PITMAN, OF PHILADELPHIA, PENNSYLVANIA.

CENTRIFUGAL PUMP.

No. 823,077.

Specification of Letters Patent.

Patented June 12, 1906.

Application filed August 9, 1905. Serial No. 273,826.

To all whom it may concern:

Be it known that I, ROBERT PITMAN, a citizen of the United States, residing at the city of Philadelphia, in the county of Philadelphia and State of Pennsylvania, have invented 5 certain new and useful Improvements in Centrifugal Pumps, of which the following is a specification.

My invention has relation to a centrifugal 10 pump; and in such connection it relates more particularly to means connected therewith and adapted to permit of the use of a loose packing or the dispensing with such packing for the pump-shaft in said type of pumps.

15 The principal objects of my invention are, first, to relieve the shaft of a centrifugal pump from the friction and wear at the point where the same turns in a packing, and thereby to extend considerably the usefulness of such a 20 pump; second, to provide for this purpose the pump-housing with a chamber interposed between the packing and piston; third, to provide the shaft of such a pump with wings or blades adapted to rotate in the chamber of 25 the pump to remove water therefrom, and thereby to prevent the same reaching the packing, and, fourth, to arrange the hub portion of the piston of the pump of a width to cover the chamber to prevent the direct in- 30 flow of water to the same and to form in conjunction with the housing of the pump an annular opening through which the water entering the chamber is discharged by the blades therein.

35 The nature and scope of my invention will be more fully understood from the following description, taken in connection with the accompanying drawings, forming part hereof, in which—

40 Figure 1 is a longitudinal sectional view of a centrifugal pump, illustrating in side elevation blades secured to the pump-shaft and a chamber formed in the pump-housing and covered by the hub portion of the piston adapted to receive the blades embodying 45 main features of my said invention; and Fig. 2 is a cross-sectional view through the said pump, illustrating in front elevation the wings arranged on the pump-shaft and the fan-wheel forming the piston of the pump.

50 Referring to the drawings, *a* and *a'* represent the sectional pump-housing, in which is adapted to rotate a fan-wheel or piston *b*, driven by a shaft *c*, supported by an extension *a²* of the section *a*. This extension *a²* also forms a stuffing-box, in which is placed

the packing *d* and is held in position therein by a gland *e*, adjustably connected with the stuffing-box by means of bolts *f*. An oil-cup *g*, secured to the extension *a²*, serves to lubricate the shaft *c* by means of a duct *g'*, as shown in Fig. 1. In the section *a* of the housing of the pump and between the piston *b* and packing *d* is arranged a chamber *h* of a diameter not larger than the hub portion *b'* of the piston *b*, which is located a slight distance from the chamber *h*, so as to form in conjunction with the section *a* of the pump-housing an annular opening *h'*, which connects the chamber *h* with the large chamber *a³* of the 6: pump in which the piston *b* rotates. The chamber *h* serves to receive blades or vanes *i*, which by means of their hub *i'* are connected with the shaft *c* and the angular position of which is such as to remove water entering the chamber *h* when the shaft *c* is rotated in the direction indicated by the arrow in Fig. 1. When the shaft *c* and piston *b* are rotated, by means not shown, water is conducted into the chamber *a³* of the pump-housing through the inlet *a⁴* and discharged therefrom through the outlet *a⁵*. The water by entering the chamber *a³* is prevented from directly entering the chamber *h* by the hub portion *b'* of the piston *b*, as will be readily understood in conjunction with Fig. 1 of the drawings, and only a comparatively small portion of the water will find its way into the chamber *h* through the annular opening *h'*. This water, however, by means of the vanes or wings *i* is as quickly discharged from the chamber *h* as the water enters the same, and hence the packing *d* is entirely relieved from the pressure of this water. By this arrangement the water is prevented from reaching the packing *d* or escaping through the same, and thus the packing can be arranged very loose or may be entirely dispensed with. Such a loose packing relieves the shaft *c* from wear and friction which is due to a tight packing, and hence the usefulness of the pump is considerably lengthened and the force to actuate the same decreased.

Having thus described the nature and objects of my invention, what I claim as new, and desire to secure by Letters Patent, is—

1. In a centrifugal pump, a housing having chambers of varying diameters communicating with each other, a shaft, a piston and vanes carried by said shaft and arranged respectively in the large and small chambers thereof, said piston adapted when rotated to

force water into and from the larger of said chambers, and said vanes adapted to remove water entering the small chamber from the larger chamber and to force the water continually back into the same so as to hold the smaller chamber substantially free from fluid.

2. In a centrifugal pump, a housing having chambers of varying diameters communicating with each other, a shaft, a piston having a hub portion and vanes carried by said shaft and arranged respectively in the large and small chambers thereof, said piston adapted when rotated to force water into and from the larger of said chambers, and its hub portion adapted to prevent the direct inflow of water into the smaller chamber, and said vanes adapted to continually remove the water entering the smaller chamber from the large chamber by forcing the same back into said chamber so as to hold the smaller chamber substantially free from fluid.

3. In a centrifugal pump, a housing having chambers of varying diameters communicating with each other, a shaft carried by and terminating within said housing, a packing arranged in said housing and surrounding said shaft, a piston having a hub portion and vanes separated from the same carried by said shaft and arranged respectively in the large and small chambers thereof, said piston adapted when rotated to force water into and from the larger of said chambers, and its hub portion adapted to prevent the direct inflow of the water into the smaller chamber and said vanes adapted to continually remove water entering the smaller chamber through said opening by forcing the same back into said larger chamber so as to prevent the water from reaching and escaping through said packing by holding the smaller chamber substantially free from fluid.

35 of the water into the smaller chamber and said vanes adapted to continually remove water

entering the smaller chamber by forcing the same back into said larger chamber so as to prevent the water from reaching and escaping through said packing by holding the smaller chamber substantially free from fluid.

4. In a centrifugal pump, a housing having chambers of varying diameters communicating with each other, a shaft carried by and terminating within said housing, a packing arranged in said housing and surrounding said shaft, a piston having a hub portion and vanes separated from the same carried by said shaft and arranged respectively in the large and small chambers thereof and said hub portion in conjunction with said housing adapted to form an annular opening connecting the large chamber with the smaller chamber, said piston adapted when rotated to force water into and from the larger of said chambers, and its hub portion adapted to prevent the direct inflow of the water into the smaller chamber and said vanes adapted to continually remove water entering the smaller chamber through said opening by forcing the same back into said larger chamber so as to prevent the water from reaching and escaping through said packing by holding the smaller chamber substantially free from fluid.

In testimony whereof I have hereunto set my signature in the presence of two subscribing witnesses.

ROBERT PITMAN.
